Primary Examiner — Dominic Simone(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a top view thereof;

FIG. 3 is a front perspective view of a shoe upper showing an alternative embodiment of my new design; and,

FIG. 4 is a top view thereof.

The broken lines immediately adjacent to the rear portion of the shaded area represent unclaimed boundaries of the design. The broken line within the shaded region represents an unclaimed panel seam. The broken lines showing the remainder of the shoe are for environmental purposes only and form no part of the claimed design.
